UNITED STATES PATENT OFFICE

134,292

DESIGN FOR A FINGERNAIL FILE

R. H. Lawson, Chicago, Ill.

Application February 23, 1942, Serial No. 105,958

Term of patent 14 years

To all whom it may concern:

Be it known that I, R. H. Lawson, a citizen of the United States, residing at Chicago, in the county of Cook and State of Illinois, have invented a new, original, and ornamental Design for a Fingernail File, of which the following is a specification, reference being had to the accompanying drawing, forming part thereof.

I claim:
The ornamental design for a fingernail file, as shown.

R. H. LAWSON.
